UNITED STATES PATENT OFFICE.

RICHARD G. BARZEN, OF KANSAS CITY, MISSOURI, ASSIGNOR TO ENGLISH BROTHERS MACHINERY COMPANY, OF KANSAS CITY, MISSOURI, A CORPORATION OF MISSOURI.

LUBRICATING SYSTEM FOR HOIST DRUMS.

Application filed January 8, 1926. Serial No. 79,985.

My invention relates to improvements in lubricating systems for hoist drums, and while particularly well adapted for use in connection with hoist drums, it may be advantageously adapted for use in the lubrication of drums revoluble on shafts of other machines.

One of the objects of my invention is to provide a novel lubrication system which 10 affords the carrying of a relatively large amount of lubricating material, which is efficient in operation, which provides novel means for preventing the passage out of the drum along the shaft on which it is revoluble 15 of oil carried by the drum, which has novel means for indicating the amount of oil to be fed at a time into the drum, which is simple, cheap, durable, not liable to get out of order, and which is adapted for embodiment in 20 hoist drums of types commonly used.

The novel features of my invention are hereinafter fully described, and claimed.

In the accompanying drawings, which 25 illustrate the preferred embodiment of my invention,

Fig. 1, is a vertical sectional view on the line 1—1 of Fig. 2, showing my improved lubricating system as applied to a hoist drum.

30 Fig. 2 is a vertical section on the line 2—2 of Fig. 1.

Fig. 3 is a section on the line 3—3 of Fig. 1.

Fig. 4 is a section on the line 4—4 of Fig. 1.

Fig. 5 is a section on the line 5—5 of Fig. 1.

35 Fig. 6 is an enlarged sectional view of a portion of one of the oil slinging collars and the drive shaft.

Similar reference characters designate similar parts in the different views.

40 1 designates the hoist drum having a hub comprising a body 2 mounted on sleeve bearing members 3, which are revoluble on a rotary drive shaft 4, the latter being adapted to be connected by clutch mechanism, not shown with a clutch drum 5 encircling the shaft 4 and fastened to one end of the drum 1.

45 The hub body 2 is provided with an intermediate oil supply chamber 6 at the middle part of the body, the ends of the latter being respectively provided with two end oil chambers 7, all said chambers encircling the axial hole of the drum in which the shaft 4 is rotatable.

50 The body 2 is provided with inner end 55 walls 8 and two partition transverse walls 9,

the latter forming the chamber 6 into three compartments, which are connected with each other by ducts 10 extending through said partition walls 9, said ducts 10 being disposed at the periphery of the chamber 6. 60 The end walls 8 are also provided with ducts 11 similarly located and communicating with the chamber 6.

Radial ducts 12 are located in each of the walls 8 and 9 and communicate at their 65 outer ends with the adjacent ducts 10 and 11. The inner ends of the ducts 12 in each wall 8 and 9 communicate with an annular groove 13, one in each of said walls, and disposed next the sleeve bearings 3 adjacent thereto. Each sleeve member 3 is provided with radial holes 14, some of which communicate with the adjacent grooves 13, and others communicating with the adjacent one of the three compartments of chamber 6. 70

In each end wall 8 are provided spaced apart radially disposed oil ducts 15 which lead inwardly from the periphery of the adjacent oil chamber 7 and away from the axis of the drum 1, and which at their inner ends 80 communicate with the adjacent ducts 12, the diameter of chamber 6 being greater than the diameters of the chambers 7 to permit of such arrangement.

As shown, the bearings 3 may have a 85 babbitt lining 3'.

Fastened to the outer ends respectively of the hub body 2 are two ring plates 16 which encircle the shaft 4 and respectively close the outer ends of the chambers 7. 90

Respectively fastened to the shaft 4 in the chambers 7 are two oil slinging collars 17, which are fastened to the shaft 4 in any manner, as by set screws 18, Fig. 6. The collars 17 are respectively disposed, preferably, at the outer side of the inner ends of the ducts 15. The function of the collars 17 is to stop the outward flow of oil on the shaft 4 and to sling such oil against the peripheries of the chambers 7, the oil entering the chambers 7 being forced by centrifugal force, when the drum 1 is revolving, through the ducts 15, 12 and 11 into the oil supply chamber 6, and when the drum is stationary, the oil in chambers 7 will run downwardly to the lower sides of the chambers 7, and through the ducts 15, 12 and 11 into the chamber 6. 100

The oil which is in the chamber 6, will, 110 when the drum is stationary, run through

the ducts 12, which are inclined from the periphery of the chamber 6 down, or which at the time extend vertically downwardly from the periphery of the chamber 6, into 5 the grooves 13, and from thence through the connecting holes 14 onto the shaft 4, thus lubricating said shaft and the inner sides of the sleeve bearings 3.

As shown in Figs. 2, 3 and 5, the inner 10 sides of the end walls 8 and each side of each partition wall 9 is provided with radially disposed recesses 19, the side walls of which converge inwardly from the periphery of the chamber 6 to the adjacent sleeve bearing 15 3, each of the latter having some of the radial holes 14 between the end and partition walls 8 and 9, so that oil flowing downwardly from those recesses which are above the horizontal center of the drum, when the 20 drum is stationary, will flow onto the bearings 3 and then through the adjacent holes 14 onto the shaft 4.

For pouring oil into the chamber 6, the inner periphery of the latter is provided 25 with an inwardly extending boss 20, Fig. 1, and Fig. 2, which has therethrough a radial hole 21, in which is fitted a nipple 22 mounted in an elbow 23, which has fitted in it a pipe 24 mounted in an exterior elbow 25, 30 in which is mounted a closure comprising a screw plug 26. The boss 20 is preferably located in the longitudinal middle of the drum 1, and communicates with the middle compartment of the chamber 6.

35 To determine when a proper amount of oil has been poured into the chamber 6, through the filling means just described, the periphery of the chamber 6 is provided, in the side of the chamber opposite to that having the boss 20, with a boss 27, which extends inwardly from the periphery, and in which is a radial hole 28 in which is fitted a nipple 29 mounted at its outer end in an elbow 30, which has mounted in it a pipe 31, the outer 40 end of which is mounted in a try cock 32 having a shut off valve 33.

When the oil is to be poured into the chamber 6, the drum is disposed with the boss 27 and try cock 32 in the lowermost 50 position, as in Fig. 1. The boss 20 and the elbow 25 will then be in the uppermost position. The plug 26 is removed and oil is poured into the chamber 6 through the elbow 25, the valve 33 at the time being 55 opened. When oil begins to flow from the try cock 32, the proper amount of oil will be in the chamber 6. The valve 33 is then closed, and the screw plug 26 replaced in the elbow 25.

60 When the drum 1 is revolved, the oil in chamber 6 will form by centrifugal force in an annular sheet on the periphery of cham-

ber 6, and will be forced into the ducts 10 and 11 and recesses 19, and oil will be forced from the chambers 7 into chamber 6, as before described. When the drum stops, the oil which is in the ducts 10 and 11 and recesses 19, which are above the horizontal plane of the axis of the drum, will flow through the ducts 12, grooves 13 and holes 70 14 onto the shaft 4, the remainder of the oil which is on the inner periphery of the chamber 6, and ducts 10 and 11 and recesses 19, which are below the horizontal plane of the axis of the drum, running to the bottom 75 of the chamber 6, as shown in Fig. 1.

It will be noted that, as shown in Figs. 1 and 3, the peripheries of the chambers 7 flare inwardly toward the ducts 15 from the ring plates 16, to insure the oil being forced inwardly away from the said plates. 80

From the foregoing description, it will be seen that every time the drum 1 stops, oil will be fed from the periphery of the chamber 6 onto and into the sleeve bearings 3 and onto the shaft 4, and when the drum is running oil will be forced centrifugally to the periphery of the drum, and, whether or not the drum is revolving, oil which has passed along the shaft 4 into the chambers 7, will be fed back therefrom into the chamber 6, 90 through the ducts 15, 12 and 11.

I do not limit my invention to the structure shown and described, as many modifications, within the scope of the appended 95 claim, may be made without departing from the spirit of my invention.

What I claim is:

In a lubricating system of the kind described, the combination with a drum having 100 a hub provided with two oil chambers at its ends respectively and an oil supply chamber intermediate of said end chambers, said hub having an axial hole therethrough, and provided with means by which oil may be carried from said end chambers into said intermediate chamber by centrifugal force, when the drum rotates and by gravity when the drum is at rest, said hub having means by 105 which oil may flow by gravity from the periphery of said intermediate chamber into said axial hole, when the drum is at rest, said hub having means by which the intermediate chamber may have oil poured into it, the hub having means for indicating when a predetermined amount of oil has been poured into the intermediate chamber, of a shaft rotatably fitted in said axial hole, and two collars mounted on said shaft in said 110 end chambers respectively.

In testimony whereof I have signed my name to this specification.

RICHARD G. BARZEN.
